UNITED STATES PATENT OFFICE.

JOSEPH E. TYNAN, OF PATERSON, NEW JERSEY.

MACHINE FOR THROWING SILK.

SPECIFICATION forming part of Letters Patent No. 364,785, dated June 14, 1887.

Application filed October 10, 1883. Renewed November 13, 1885. Again renewed November 9, 1886. Serial No. 218,416. (No model.)

To all whom it may concern:

Be it known that I, JOSEPH E. TYNAN, of Paterson, in the county of Passaic and State of New Jersey, have invented an Improvement 5 in Machines for Throwing Silk, of which the following is a specification.

In machines for throwing silk in the doubling and spinning employed in making the "organzine" warps the threads are drawn off 10 two or more spools and brought together and twisted and wound upon a bobbin. The spools from which the threads are drawn are rotated in one direction to twist the threads, and the spool or bobbin on which the threads are 15 wound is rotated in the other direction to lay the threads together and twist them as the winding progresses.

My present invention relates to the mechanism for effecting the before-named object in 20 a more uniform and reliable manner than heretofore, and for stopping the parts if a thread breaks, or if the ring-traveler flies off, or if the driving-belt breaks or slips.

In the drawings, Figure 1 is an elevation of 25 the parts of a silk-throwing machine with the present improvements thereon and with the rails and belt-shifter in section. Fig. 2 is a front elevation of the same. Fig. 3 is a plan of the spools and friction-disks and the adjustment devices for operating the same. Fig. 4 is a sectional plan at the line xx , Fig. 1. Fig. 5 is a sectional plan at the line yy of Figs. 1 and 2. Fig. 6 is a plan of the feed-roller and the pivoted beam. Fig. 7 is a detached view 35 of the bearing for the feed-roller shaft. Fig. 8 is a section in larger size of the spindle-rail bolster, bolster-sockets, steps, and oil-cups, the spindles being in elevation; and Fig. 9 is a section of one of the bolster-sockets and 40 part of the spindle-rail.

The spools a^5 and b^5 contain the threads that are to be twisted and laid together, and the spool or bobbin P receives the threads as twisted together and wound upon such spool.

45 The spindles a^5 b^5 Q receive the respective spools, a^4 b^4 P . The spindles a^5 b^5 will usually be slightly tapering, so that the spools will be held thereon when pressed down to place.

The ring and traveler h and rail c are to be 50 of ordinary character, and will be raised and

lowered to lay the threads upon the spool P by the usual mechanism.

Upon the spindle Q there is a fast pulley, T , having a disk, c^4 , and below it is a loose pulley, U , upon which the driving-belt w^2 is shifted 55 when the belt-shifter is moved to stop the spindles.

The spindles a^5 b^5 have upon them, respectively, the friction-disks a^6 b^6 , the edges of which are in contact with the edges of the disk c^4 of the fast pulley T , and hence the spindles a^5 b^5 receive motion from this pulley T ; but they revolve in the opposite direction to the spindle Q , as indicated by the arrows in Fig. 3. The tension of the belt tends to keep the 65 edge of disk c^4 of the pulley T in contact with the edges of friction-disks a^6 b^6 , and the parts are adjustable, as hereinafter explained.

The bolster-sockets form oil-receptacles. The bolster-sockets B^4 for the spindles a^5 b^5 70 are made with flanges 44, resting upon the bolster rail a , and with nuts 45 below such rail. The holes through the rail for these bolster-sockets are made larger than the socket, or elongated in the direction of the spindle Q , so 75 that the bolster-sockets B^4 can be adjusted toward this spindle Q to regulate the contact of the edges of the friction-disks, and the parts are held by the nuts 45 and by the screws 46, (see detached plan, Fig. 9,) passing through 80 the bolster-rail and acting against the side of each socket to press it toward the spindle Q . There are preferably two screws, 46, to each bolster-socket, to hold the parts firmly after 85 they are adjusted.

The bolster-socket R , where it passes through the bolster-rail a , is made with an enlargement above the rail to form the oil-cup r , and also to give a bearing upon the surface of the bolster-rail to retain the bolster and spindle in a 90 vertical position, and the hole through the rail is larger than the bolster, so that the bolster-socket R and spindle Q may be drawn toward the spindles a^5 b^5 by the action of the belt w^2 , which passes around the fast pulley T to 95 insure the necessary friction between the friction-disks a^6 b^6 and disk c^4 of the pulley T and obtain uniformity of rotation in the directions stated. There is a helical or spiral spring, 50, between the nut 51 of the bolster-socket R and 100

the under side of the bolster-rail to allow the parts to yield slightly, but to maintain the bolster and spindle in a vertical position, and a pin, 52, in the bolster-socket passing into a slot in the rail, prevents the bolster-socket R revolving.

The tubular bolsters s are similarly made for all the spindles a⁵ b⁵ Q. They are adapted to receive the lower ends of the spindles, and to each one has a hemispherical bearing, v⁶, around the central portion passing into a similarly-shaped recess at the top of the bolster-socket, and there is to be a hole, 60, Fig. 8, through said bearing v⁶ for oil to flow down, and a pin passing through the upper end of the bolster-socket into the bearing, as at 39, to prevent the bolster revolving. By this construction the bolster is hung by its hemispherical bearing, and this is in line, or nearly so, with the fast pulley and the friction-disks, so that the spindle and its tubular bolster may vibrate above or below the bearing v⁶ without varying the action of the friction-disks, the edges of the friction-disks being preferably segments of globes having the same center as the hemispherical bearings.

At the lower end of the bolster for the spindle Q there is a screw-step, b¹⁰. By screwing this step up or down the spindle will be raised or lowered, and thereby the position of the friction-disk c¹ with reference to the disks a⁶ b⁶ may be adjusted with the greatest accuracy, and at the same time the pulleys T and U are kept from touching each other. The spring p, 35 that passes vertically up through the lower end of the bolster-socket, enters a hole in the lower end of the screw-step b¹⁰. The screw-step slides freely down over the end of the spring, so that the weight of the parts is taken upon the bearing v⁶. The spring p tends to keep the bolster and spindle vertical; but if the bobbin is not true the spring yields and allows the bobbin and spindle to find their own axis of rotation. There are openings 61 in the lower part of the bolster to allow the oil to pass into the spindle from the bolster-socket.

Around the spindle Q, below the fast pulley T, is the loose pulley U, that has a hub that fits upon the outside of the sleeve of the bolster-socket R, and this hub revolves in the oil box or cup r, and there is a flange, r⁵, at the lower end of this loose pulley U, to prevent the cord or belt w coming into contact with the oil cup r, and the downward flange r⁷, within the oil-cup, prevents oil being thrown out by centrifugal action, and the flange r⁸ aids in excluding dust. There is a cylindrical dam, r⁸, within the oil-cup, having holes to permit the oil to pass through into the inner cup, and by the duct 70 into the bolster to lubricate the spindle. This dam r⁸ prevents air-bubbles and froth, that may form on the surface of the oil at the loose pulley, causing the oil to be displaced from the oil-cup, because the air-bubbles as they accumulate and pass over the

dam are broken to a large extent by the upper edge of said dam.

The driving-belt w², driving-shaft w, tightening-pulley i, lever i², weight i³, pivot 30, 70 and jaw-block 64 on the rail 31 are similar to those in my application, Serial No. 108,580, filed October 10, 1883; but when used as in the present application the movable weight upon the tightener causes the belt w² to draw the spindle Q and its disk c¹ toward the friction-disks a⁶ b⁶ with a uniform power, and thus uniformity of rotation is obtained.

w³ is the belt for revolving a spindle of the range of spindles on the opposite side of the machine. There is a standard, v³, and a head or disk, v⁴, (see Figs. 1 and 3,) above the friction-disks a⁶ b⁶, but not in contact therewith, which prevents the spindle Q or a⁶ or b⁶ being raised when a spool is pulled off. This is not claimed herein, as the same is shown in a prior application filed August 24, 1882, and allowed July 19, 1883. The drop-bar m passes through the forks or jaws 7 and 8, that are attached to and project laterally from the respective rails, a and b, and each jaw has a pin across through it to confine the bar m in place; but said bar m is free to slide vertically. By the removal of the pins that confine either drop-bar m in the silk-throwing machine such bar m can be taken out without stopping the machine. The drop-bar m is notched at the fork 7, and the spring 9 presses the notch of such drop-bar upon the said fork to hold up the drop-bar, and upon the drop-bar m there is the belt-shifter n¹ and the friction-brake n to stop the rotation of the spindles. The three spindles are stopped by one brake acting upon the disk c¹ of the fast pulley T. The shaft k and rollers k' are rotated at the proper relative speed to the spindles, so as to regulate the twist by the extent of feed movement in proportion to the rotation of the spindles. I have shown a belt, w⁴, as the means for communicating motion from the driving-shaft W to the shaft k; but gearing might be substituted for the belt. w⁵ is the belt for rotating the shaft k of the range of spindles on the opposite side of the machine. This opposite range is not shown in the drawings. The feed-roller f is upon a shaft, f¹, that is in the slotted bearings f² and f³, and said roller f rests upon the roller k'. It is the most convenient to employ a shaft that is longer at one side of the feed-roller than the other, as shown, and to prevent the feed-roller being tipped by the leverage of the long end of the shaft, and to cause the feed-roller f to take an even bearing upon roller k', I make use of the adjustable forked bearing j', Fig. 7, that is attached to the standard f⁴ by a slot and screw and may be raised or lowered.

At the upper end of the drop-bar m there is a frame, 10, and a beam, l, such frame and beam being connected by the pivot 6. The beam l is provided at its inner end with a projecting rod and adjustable weight, l⁷, and at its

outer end it is bifurcated or provided with a long arm, l^2 , and a short arm, l^3 .

At the outer end of the long arm l^2 is a finger, l^8 , which bears lightly upon the thread as it passes from the feed-roller f to the fixed eye or hook l^9 , and thence to the ring-traveler. This short arm l^3 is provided with a tooth or pawl, 17, and upon the feed-roller f are the pins 18. If the thread break or the ring-traveler break or fly off the ring, the beam l swings and the front end descends, bringing the pawl 17 into the path of one of the pins 18, and said pin, striking the end of the pawl, pushes the beam endwise and moves the upper end of the drop-bar m , so as to cause it to slip off its support at the fork 7 and fall or be depressed, thus stopping the spindles by shifting the belt to the loose pulley and by the pressure of the friction-brake upon the disk c^1 . The threads that pass up from the spools a^4 b^4 go through eyes l^{10} , and the threads that pass down to the spool P go through the eye l^{11} . I find it convenient to place these eyes upon wires or lever-arms extending out from the hinged stock l^2 , Fig. 5, at the back of which is a lifter, l^{13} , below the bracket l^4 upon the drop-bar m ; hence when such bar m is dropped the lever-eyes l^{10} l^{11} will be moved up into an inclined position, and after the thread has been mended the drop-bar is raised by forcing down the lever-eyes.

Upon the drop-bar m there is a second frame, n^5 , to which two beams, n^6 , are pivoted, each of which has a hook, n^7 , at one end and an adjustable counterpoise, 62, at the other end, and a tooth, n^8 , upon the body part of the beam. The rods n^{18} and hooks l^{18} project horizontally from the plate n^9 upon the rail t^4 . The threads from the spools a^4 and b^4 pass up through the eyes or hooks l^{10} l^{18} , across over the hooks n^7 at the ends of the beams n^6 , beneath the rods n^{18} , that stand out from the plate n^9 , thence they go close together up over and around the feed-roller f , and out below the finger l^8 on the beam l , over the hook l^9 , and down through the eye l^{11} to the traveler and spool P , on which the organzine thread is wound. As the threads are drawn off the spools a^4 and b^4 they are twisted in one direction by the revolution of such spools, and as the two threads after passing over the feed-roller f descend they are laid together and twisted to form a finished thread by the spindle Q rotating in the opposite direction to the spindles a^4 b^4 , and if either of the threads break the hook at the end of the beam n^6 , that had been beneath such thread, rises by the action of its counter-weight 62, bringing the tooth n^8 against one of the stops 48, that project at such side of the roller k' , and the drop-bar m is pushed back and falls, stopping the further revolution of the spindles. Whenever the bar m drops, the pivots 6 of the beam l are carried down with it and the beam l comes into contact with a pin, 19, that projects laterally from the standard f^6 , and said beam becomes a lever and the pin 19 a ful-

crum, and such beam l acts below the shaft of the feed-roller f to raise the same, and thereby stop the revolution of the feed-roller f and the feed of the thread. The threads may pass up in front of a guide-bar, n^{10} , Fig. 1. This guide-bar is partially removed in Fig. 2. It is specially to prevent a broken thread catching upon the roller k' . The fingers m^8 , that project from the drop-bar m , extend over the spools a^4 and b^4 , near one edge of each. As the spools revolve in the direction of the arrow the threads pass by the sides of these fingers, and when the spools are stopped for any of the causes mentioned these fingers descend with the drop-bar and come close to the spools and prevent the momentum or the twist causing the threads to unwind or kink. The bar m^9 , projecting forward from the upper part of the drop-bar m , is guided in a slot in the plate n^9 to steady such drop-bar and prevent the same partially rotating in its bearings. The fingers m^8 may be bent into a curved form at the end, and set in a position for the threads to rub against them as the spools are revolving, which will tend to detain the thread as it unwinds in contact with the head of the spool, and apply to the same a slight and nearly-uniform tension. This tension is useful, as it prevents the weight 62 raising the hook n^7 and tooth n^8 so long as the tension is maintained, the thread passing over the hook n^7 . When the driving-band w^2 of a spindle breaks, the twisting and winding operations are instantly stopped, and the thread, becoming slack between the receiving-bobbin and the feed-roll by the continuation of the movement of the feed-roller f , the finger l^8 at the end of the lever l is unsupported and descends, and the lever l operates on the stop motion, as aforesaid, bringing the pawl 17 into action, and the feeding of the thread is instantly stopped, thereby preventing waste, because the spinning, doubling, and twisting and winding operations are all stopped when either a single or a double thread breaks or when a belt slips or breaks.

I have represented herein the entire mechanism connected with this silk-throwing machine, and I remark that all the novel and patentable features herein shown are my invention; but as the devices connected with the spindles, bolsters, and bolster-sockets form the subject of a separate application, Serial No. 131,105, the same are not herein claimed.

The ring-traveler l , especially in silk-machines, is light and liable to wear out; hence it is of great importance to stop the machine as soon as a traveler breaks or flies off. This is instantly effected by the means before described, because the twisted thread becomes slack and the detector l^8 comes into action.

In Letters Patent No. 326,531, granted to me September 15, 1885, (the application for which was pending at the same time as my application of which the present is a renewal,) there is a faller, lever, feed-roller, and means for re-

volving the roller, a frame, stop-motion rod, and spindles having tight and loose pulleys and friction-pulleys; but the claim to such is in a limited form, bringing in other features in combination, which limited combination I do not herein claim.

I claim as my invention—

1. The combination, with the spindles Q a^5 b^5 and friction-disks c^4 a^6 b^6 , of a driving-belt, fast pulley T, loose pulley U, a belt-shifter, a friction-brake, a drop-bar, and mechanism, substantially as specified, to disengage the drop-bar when either thread breaks, substantially as set forth.
- 15 2. The combination, with the spindles Q a^5 b^5 and means for revolving the winding-up spindle Q in one direction and the spindles a^5 b^5 in the opposite direction, of the feed-roller f, provided with pins 18, the beam l, having a pawl, 17, the drop-bar m, and the standard f⁶ and pin 19, substantially as set forth.

3. The combination, with the shaft k, of the roller k', the driving-shaft W, means for rotating the shaft k from the driving-shaft W, the pivoted beam n⁸, having the tooth n⁹ and hook n⁷, the stops 48 upon the roller k', and the guides l⁸ n¹⁸ for the thread, and the drop-bar m, and fork 7, substantially as set forth.

4. The combination, with the drop-bar m, provided with the bracket l¹, of the stock l², lifter l³, and eyes l¹⁰ l¹¹, the rail t⁴, and the hinge to connect the stock l² to the rail, substantially as set forth.

5. The combination, with the spindles a^5 b^5 for the spools, of the drop-bar m, and the fingers m⁸, that project above such spools and are attached to such drop-bar, substantially as specified.

6. The combination, with the spindles a^5 b^5 and friction-disks a^6 b^6 , of the friction-disk c¹, spindle Q, pulley T, belt w², pulleys w and i, and weighted lever r, substantially as set forth.

7. The combination of spindles for the spools that contain the silk to bespun and from which the threads are drawn off in contact with one end of the spools, a spindle for the spool upon which the double threads are wound after being twisted together, a ring and traveler for the twisted threads, a feed-roller around which the threads are passed, a stop-motion beam acting upon the thread between the feed-roller and ring-traveler, and mechanism for rotating said spindles and the feed-roller and for stopping the spindles, their spools, and the feed-roller simultaneously when the threads be-

come slack after passing around the feed-roller, as set forth.

8. The combination, with the spindle for the winding-spool and the belt for revolving the spindle, of a feed-roller, a finger acting against the doubled thread between the feed-roller and the winding-spool, and devices acting on the feed-roller to stop the feed of the thread whenever the said thread becomes slack at the finger, substantially as set forth.

65 9. The combination, with the feed-roller for drawing the threads from the spools, and the spindle for twisting the threads together and for rotating the spool upon which the twisted threads are wound, of a ring-traveler for such threads, fallers for the threads between the feed-roller and the spools, a detector between the feed-roller and the traveler, and a stop-motion brought into action by the breaking of either single thread or the slackening or breaking of the doubled thread, substantially as specified.

10. The combination, with two spindles and means for rotating the same to twist the single threads, of a spindle for twisting the two threads together and for receiving a spool upon which the twisted threads are wound up, a driving-roller, and a feeding-roller moved by said driver for drawing the threads off the spools, fallers applied to such threads between the spools and the feeding-roller, and a detector applied to the two threads after they are brought together between the feed-roller and the winding-spool, and a stop-motion brought into action by either the fallers or the detector to stop all the spindles and to separate the feed-roller from the driving-roller in case either single thread breaks or the double thread breaks or becomes slack, substantially as specified.

95 11. The combination, with the rail and the spindles Q a^5 b^5 , of frictional disks, one upon each spindle, fast and loose pulleys on one of the spindles, and bolsters for each spindle, the lower end of the bolster of the driving-pulley spindle passing through the rail, so that it may be moved to maintain contact between the friction-disks, substantially as set forth.

100 Signed by me this 1st day of October, A.D. 1883.
